UNITED STATES PATENT OFFICE.

FRED V. HART, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF AND MACHINE FOR HANDLING HEELS.

Application filed December 31, 1920. Serial No. 434,237.

To all whom it may concern:

Be it known that I, FRED V. HART, a citizen of the United States, residing at Lynn, in the county of Essex and State of Massachusetts, have invented certain new and useful Improvements in Methods of and Machines for Handling Heels; and I do hereby declare the following to be a full, clear, and exact description of the invention, such as will enable others skilled in the art to which it appertains to make and use the same.

The present invention relates to methods of handling or assembling heels, or the like, and to apparatus for practicing the same, and it has special reference to the pressing of freshly pasted heels during the setting of the paste, although in many of its aspects, it is not so restricted, but may be applicable to other pieces or articles of shoe stock and for other purposes.

In applicant's co-pending application, Serial No. 314,219, filed July 30, 1919, and assigned to the United Shoe Machinery Corporation, is set forth a so-called tube-type heel press comprising a long tube-like structure consisting of close fitting inwardly-pressed longitudinal members or walls between which freshly pasted heels are made to progress in column formation, the walls frictionally resisting the passage of the heels so that the component lifts are held firmly together under pressure during the drying or setting of the paste. Such presses have heretofore been constructed in the form of a single continuous tube or guideway which has been necessarily of considerable length in order that the paste should become thoroughly dried during the passage of the heels through the tube.

One object of the present invention is to provide an improved heel press of the above named general character which shall be of such compact construction that it will occupy a minimum amount of floor space when installed in a factory, and which shall also be so constructed and arranged that the heels are maintained under pressure for a sufficient period of time to insure the proper drying of the paste.

With this object in view, one feature of the invention contemplates the construction

of a tube-type heel press in a plurality of compactly arranged, separated sections or units of short extent that are adapted to be successively moved into a loading position at which the heels are introduced into the press tubes.

In the co-pending application above referred to, a device is provided for automatically loading the single tube-like press with wedge heels which, although presented in similar positions to the loading device, are delivered to the press tube, in repeated series of four heels each, in predetermined dissimilar positions in accordance with a method of stacking wedge heels illustrated, described and claimed in a co-pending application, Serial No. 258,722, filed October 18, 1918, by John B. Hadaway and assigned to the United Shoe Machinery Corporation. The practice of this Hadaway method of stacking heels not only permits, but makes commercially feasible, the pressing of heels of wedge form in a tube-type press, inasmuch as the heels of each series are arranged in such dissimilar position that the heels are stacked in a straight row with their adjacent faces in full engagement over their entire area. Therefore, the endwise pressures applied to the column of heels in the press tube are distributed evenly over substantially the entire area of every heel face so that the individual heels, and also the component lifts thereof, are evenly and uniformly pressed.

With this in mind, another object of the present invention is to devise a simple way of utilizing, and hence securing the benefits of, the Hadaway method of stacking wedge heels in connection with a compactly arranged multiple tube heel press, while subjecting all heels to the same operating conditions and therefore securing a uniform product.

Accordingly, another feature of the invention resides in a method of handling, assembling or pressing heels which comprises arranging the heels in repeated like series, in each of which the heels are arranged in predetermined relation, and in consecutively distributing the heels so arranged in regular order and one at a time in stacked relation in the several press tubes of the heel press,

the number of press tubes having such a relation to the number of heels in a series that in each press tube a stack of heels is progressively produced in which the same 5 Hadaway serial relation of heels obtains.

In a different aspect, another object of the invention is to provide a multiple tube heel press, of the character hereinbefore mentioned, with an automatic loading or positioning device, such as already referred to, which shall cooperate in such time relation with respect to the several tube presses, that applicant's above indicated method may be practiced with facility and a uniform 10 quality of product be assured.

Accordingly, another feature of the invention contemplates a rotary loading or positioning device having four heel adjusting clamps for arranging the heels in repeated like series of four dissimilarly positioned heels each, and a multiple tube heel press comprising a rotary support carrying five press tubes, or one more than any multiple of the heels in a series. The positioning device and the press tubes are mechanically connected to rotate concurrently in steps, respectively of one-quarter and one-fifth of a revolution, after each heel is delivered to a press tube, whereby the desired 20 ends are attained.

Other objects of the invention are to provide improvements in tube-type presses, to provide means, adapted particularly for multiple tube presses carried by a rotary 30 support, for controlling the discharge of the heels from the respective press tubes, and to provide improved mechanism for receiving the heels delivered by the heel press and transferring them in definite positions to a 40 position of deposit.

To the accomplishment of the objects hereinbefore mentioned, and such others as may hereafter appear, as will be apparent to those skilled in the art, the invention comprises the novel features, arrangements and 45 combinations of parts hereinafter described, and then particularly pointed out in the appended claims.

While, for illustrative purposes, the invention has been, and will hereinafter be set forth as specifically applied to the handling and pressing of heels, it should be understood that certain features of the invention are equally applicable to shoe stock of different characteristics and forms and, moreover, may be utilized to advantage for various other purposes. Therefore, only such limitations should be imposed as are indicated in the appended claims.

The features of the invention will be readily understood from the accompanying drawings, illustrating the invention in its preferred form, and from the following detailed description of the construction shown therein.

In the drawings Figure 1 is a view, in side elevation, of a machine constructed in accordance with the present invention, the central portion of the machine being broken away; Fig. 2 is a view, in end elevation and on enlarged scale, of the machine looking from the left in Fig. 1; Fig. 3 is a sectional view on a further enlarged scale, the view being taken substantially on the line 3—3 of Fig. 1; Fig. 4 is a detail view in side elevation of the receiving end of one of the tube-like sections of the press, showing said section in loading position; Fig. 5 is a top plan view of the parts shown in Fig. 4; Fig. 6 is a sectional view taken substantially on the line 6—6 of Fig. 3 showing the parts on a still further enlarged scale; Fig. 7 is a view in side elevation, partly in section, of a portion of the mechanism at the delivery end of the machine; Fig. 8 is a view, partly in section and partly in elevation, of a portion of the mechanism shown in Fig. 7, the section being taken substantially on the line 8—8 of said figure; Fig. 9 is a top plan view of the delivery platform and a portion of the transfer mechanism; Fig. 10 is a sectional view taken substantially on the line 10—10 of Fig. 7; Fig. 11 is a detail view in side elevation of the delivery end of one of the tube-like sections of the press, said section being shown in unloading position; Fig. 12 is a sectional view taken on the line 12—12 of Fig. 11; Figs. 13, 14 and 15 are detail views, in plan and front and side elevations, respectively, of the heel clamps employed in both the loading and unloading mechanisms; Fig. 16 is a detail view, in side elevation, of four heels arranged in the positions in which they are successively presented by the operator to the loading mechanism of the machine; and Fig. 17 is a diagrammatic view illustrating the method of stacking heels which constitutes one of the features of the present invention.

As shown in Fig. 1, the invention comprises, in general, a multiple-unit heel press 20 consisting of a plurality of horizontal tube-like presses or receptacles 22, which are supported in parallel relation, equidistant from each other and from a common horizontal axis about which the presses are rotated step-by-step to bring their receiving ends successively into heel-receiving position at a loading station 24; a heel-positioning and loading mechanism 26, which receives uniformly positioned, freshly pasted heels, delivers them successively in repeated series of predetermined dissimilar positions at the loading station 24 and loads them progressively in the several presses 22 as the latter are successively brought into heel-receiving position; unloading and position-changing mechanism 28, which receives the dissimilarly positioned heels after they have passed through the heel press and have been 125 130

discharged therefrom at an unloading station 30, restores the heels to uniform positions and delivers them, thus uniformly positioned, to a suitable receiver such as the 5 platform 32 at a transfer station 34; and transfer mechanism 36 which removes the heels individually from the platform 32, uniformly changes their positions and deposits them successively in similar positions 10 upon a conveyer 38 by means of which they may be carried to a heel compressor.

The entire mechanism is mounted upon a base 40, from one end of which rises a yoke-shaped support 42 upon which the loading 15 mechanism 26 is mounted. Two standards 44 and 46 are secured to the opposite end of the base 40 and serve to support the unloading mechanism 28 and the transfer mechanism 36. The heel press 20 is located between the loading mechanism 26 and the unloading mechanism 28 and extends horizontally above the base 40, its several tube-like 20 presses or receptacles 22 being carried upon a rotatable support comprising a plurality 25 of supporting devices or spiders 48 which are mounted upon a horizontal shaft 50. The shaft 50 is journaled at one end in a suitable bearing formed in a plate 52 that is secured to the front of the standard 42 and 30 its opposite end in a bearing formed in a plate 54 that is secured to the support 44. The shaft 50 is driven intermittently through suitable connections with the loading mechanism 26, to be hereinafter described, so as to bring the heel press units 22 successively 35 into heel receiving position.

The heel press units or receptacles 22 which constitute the heel press 20, and which are five in number, are adapted to engage the 40 lateral edges of a column of freshly pasted heels and frictionally resist their passage as they are forced therethrough, so that the component lifts of the heels will be firmly held together during the drying or setting 45 of the paste. To this end each press 22 is, in general, similar to the single tube-like heel press described in applicant's above mentioned application, the presses severally consisting of box-like tubes each having four inwardly and yieldingly pressed side members. In the present construction, however, each side member of each of the five heel presses 50 is pressed inwardly independently of the other side members.

55 Each of the heel press units 22 comprises four relatively movable side members or walls 58, 60, 62 and 64 (Fig. 3) which are mounted in the supporting devices or spiders 48. The side walls are arranged in pairs, the inner faces of each pair being oppositely disposed with respect to one another and being disposed substantially at right angles with relation to the inner faces of the other pair. Each of the supporting devices 48, in 60 which the heel presses or receptacles 22 are

mounted, comprises a pair of disk-like spiders 68 and 70 (Figs. 1, 3 and 6), which are arranged close to each other as shown in Fig. 1 and are rigidly secured to the shaft 50. The supporting spiders 68 and 70 are 70 provided with registering apertures 72 (Fig. 3) through which the heel press tube 22 extends, there being five such apertures formed in each spider to receive the five heel press units.

The side members or walls 58 of the heel press units or individual presses 22 are each carried by a plurality of supporting arms 74 which are pivotally mounted between the several pairs of spiders 68 and 70 to permit adjustment of the oppositely disposed side members of each press toward and from each other for the purpose of varying the size of the presses to accommodate heels of different sizes. As shown in Figs. 3 and 6, each arm 74 is mounted to turn freely upon one of a plurality of short horizontal shafts 76 which are disposed in coaxial relation and are journaled in bearings in the several pairs of spiders. The side members or walls 60 which are opposed to the side walls 58 are carried by a plurality of arms 78 which are similar to the arms 74 and are mounted to turn on the shafts 76 beside the arms 74. The side walls 62 of each heel press unit are supported by a series of arms 80 which are pivotally mounted between each pair of spiders 68 and 70. The arms 80 which support four of the press units are severally mounted to turn upon short horizontal shafts 82, these shafts being severally secured at one end to the supporting spiders 70. The arms 80 supporting the fifth press unit are secured to a single horizontal shaft 83 which extends substantially throughout the length of the heel press and is journaled in bearings in each of the several sets of spiders 68 and 70. The side walls 64 which are opposed to the side walls 62 are supported by a series of arms 84 that are severally secured to the short shafts 76 adjacent the outer sides of the spiders 70.

The manner in which the four side walls of each heel press are attached to their respective series of supporting arms is identical and consequently it will be necessary to describe in detail the mounting of only one side wall to one of its supporting arms. As shown in Fig. 3, the side wall 58 is pivotally and yieldingly mounted upon its supporting arm 74. To this end, the supporting arm 74 is forked at its outer end, as indicated at 88, to straddle a bolt 90 which extends through the side wall perpendicular to its working face and is fixed thereto. The bolt 90 projects outwardly from the side wall and extends transversely through a stud 92 which is mounted to turn freely in the forked end of the supporting arm. The free end of the bolt 90 is screw-threaded to receive a nut 94

75

80

85

90

100

105

110

115

120

125

130

and a lock-nut 96 which retain the bolt in the stud 92, a suitable washer 98 being interposed between the stud 92 and the nut 94. To permit the side wall to be forced yieldingly toward the opposite side wall so as to apply a lateral pressure to the stack of heels in the heel press the hole in the side wall through which the bolt 90 extends is counterbored to form a recess 100 in which is received a coiled spring 102 which surrounds the bolt 90 between the base of the recess 100 and the stud 92. Suitable washers 104 are provided at the opposite ends of the spring 102 to take the thrust of the spring.

15 To accommodate different sizes of heels in the individual heel presses 22, the oppositely disposed members of each pair of side walls are adjustable toward and from each other. The opposed side walls 58 and 60 of each of the five heel press units are adjusted concurrently, as are also the opposed side walls 62 and 64. The means for adjusting the side walls 58 and 60 concurrently will now be described. The arms 74 upon which the side walls 58 are supported are extended inwardly beyond the pivot studs 76, as indicated at 108 in Figs. 3 and 6. The rounded free ends of the extensions 108 of the series of arms 74 between each pair of supporting spiders 68 and 70 are received in a plurality of notches 110 which are equally spaced apart in the periphery of an adjusting disk 112 which is mounted to turn freely on the shaft between said spiders. The arms 78 which support the side walls 60 are similarly extended inwardly beyond the pivot studs 76, as indicated at 114. The rounded free extremities of the extensions 114 project into peripheral notches 116 which are formed in an adjusting disk 118 which is mounted to turn on the shaft 50 alongside of the disk 112. There is one pair of disks 112 and 118 for adjusting each of said series of supporting arms.

45 For the purpose of turning the adjusting disks 112 to adjust the side walls 58 inwardly or outwardly, one of the supporting arms 74 of the series between each pair of supporting spiders 68 and 70 is provided with an outward extension 120 of one of its forked ends 88. The extensions 120 of the arms 74 are severally connected by means of links 122 with a series of arms 124 which are secured to a shaft 128. The shaft 128 extends substantially throughout the length of the heel press and is journaled in bearings in each pair of supporting spiders 68 and 70 and the arms 124 are secured to the shaft 128 between said bearings. In a like manner, one of the supporting arms 78 of the series between each pair of supporting spiders 68 and 70 is provided with an outward extension 130 of one of its forked ends. The extensions 130 are connected by means 60 of links 132 with an arm 134 projecting in-

wardly from the shaft 128. For the purpose of turning the shaft 128 to actuate the arms 74 and 78, a worm wheel 136 is secured to the shaft 128 adjacent the outer side of the spider 70 which is nearest the loading end of the press. Intermeshing with the worm wheel 136 is a worm 138 secured to a short radial shaft 140 which is journaled in bearings upon said supporting spider 70. The outer end of the shaft 140 is squared, as indicated at 142, to receive an adjusting wrench by means of which the worm may be turned to effect the required adjustment therein. By means of the above described construction, it will be seen that as the worm 138 is turned to rotate the shaft 128, the several arms 74 which are connected with the shaft 128 through the links 122 and the arms 124 will be swung in one direction, while the several arms 78 which are connected with the shaft 128 through the links 132 and the arms 134 will be swung in the opposite direction. As the arms 74 and 78 are thus swung, said arms will cause the adjusting disks 112 and 118 to be rotated in opposite directions upon the shaft 50. As the disks 112 and 118 are rotated by the extensions of the particular arms 74 and 78 above referred to all the rest of the arms 74 and 78 which are operatively connected with said disks will swing concurrently and proportionately with the first mentioned arms. As a result, the opposed side walls 58 and 60 of all five heel press units 22 will be adjusted concurrently and proportionately toward or from each other.

50 The side walls 62 and 64 of the five heel guides are also concurrently adjusted by means of the following devices. The arms 80 upon which the side walls 62 are mounted are provided with extensions 146 which are so disposed with respect to the arms 80 that said arms, together with the extensions, constitute bell crank levers. The inner ends of the extensions 146 of the series of arms 80 which are located between a pair of spiders 68 and 70 are equally spaced apart in peripheral notches 148 in an adjusting disk 150 which is mounted to turn freely on the shaft 50. One of these disks is located adjacent the outer side of each spider 70 and is confined between a hub on the spider and a collar 152 which is pinned to the shaft 50. Each adjusting disk 150 is provided also with a set of slots 154 (Fig. 3) which are equidistant from each other and from the shaft 50. The slots 154 are entered by studs 156 projecting laterally from extensions 158 of one of the forked ends of each supporting arm 84 which supports the side walls 64. The disks 150 are rotated by one of the extensions 146 of the series located between each pair of spiders to effect the adjustment of the side walls 62 and 64. To this end, a worm wheel 160 is secured to the 65

end of the shaft 83 at the loading end of the press. The teeth of the worm wheel 160 are cooperatively engaged by the teeth of the worm gear 162, said worm being fast upon 5 a short radial shaft 164 which is journaled in bearings 166 on the outer side of the spider 68 which is nearest the loading mechanism. The outer end of the shaft 164 is squared, as indicated at 168, to receive a 10 wrench or crank by means of which it may be turned. As the shaft 83 is turned by the above described worm gearing, the extensions 146 of the arms 80 upon said shaft are swung to rotate the series of disks 150 in 15 one direction or the other. As the disks 150 are thus rotated, all the rest of the arms 80 are swung concurrently and proportionally, with the particular set of said arms just referred to, thus causing all five sets of side 20 walls 62 and 64 to be adjusted concurrently and proportionately toward or from each other. It will be seen that by means of the devices above described for effecting the adjustment of the opposed side walls of the 25 heel presses, the side walls will be securely held in their adjusted positions.

The adjacent side walls of each heel guide are at all times maintained with their inner faces perpendicular to each other by means 30 of two sets of angle rods 172 and 174 having arms disposed at right angles to each other. The angle rods 172 are disposed at intervals throughout the length of the side walls 58 and 64. One arm of each angle 35 rod is adapted to slide longitudinally in a guideway which extends transversely through the side wall 58 from one narrow longitudinal edge thereof to the other, while the other arm of each angle rod is adapted 40 to slide in a guideway similarly formed in the side wall 64. The angle rods 174 are arranged with respect to the side walls 60 and 62 in the same manner as that in which the set of angle rods 172 are arranged with respect to the side walls 58 and 64. As the 45 side walls 58 and 60 are adjusted toward or from each other, one arm of each of the rods 172 and 174 will slide inwardly or outwardly within the guideways in the side walls 62 and 64 and as the side walls 62 and 64 are adjusted toward and from each other, the other arms of each of the angle rods 172 and 174 will slide relatively to the side walls 58 and 60. In this way the perpendicular 50 relation of the inner faces of the four side walls of each of the individual heel presses will be maintained, irrespective of the adjusted positions of said walls.

The heels are automatically loaded into 60 the individual units or tubes of the heel press by means of the loading mechanism 26 which is located adjacent the receiving ends of the press tubes. The operator supplies freshly pasted heels, in similar positions to the loading device 26 which loads

the heels successively in dissimilar positions into the tubes or sections of the heel press. With the exception of the improved construction of the clamps in which the heels are held, the construction and mode of operation of the loading mechanism 26 is the same as that disclosed in applicant's hereinbefore mentioned co-pending application, Serial No. 314,219. Therefore, only a brief and general description of the common features of the two mechanisms will be given, reference being had to said application for a more detailed description, if desired.

The loading mechanism 26, like that of said co-pending application, includes a positioning device comprising a rotatable carrier disk 180 (Fig. 2) which is secured to a horizontal shaft 182 and which is provided with four heel clamps 184, the latter being spaced 90° apart upon the carrier. The carrier disk 180 is rotated step-by-step through quarter revolutions to bring the heel clamps 184 successively into position to receive a heel at a receiving station 186, by means of suitable mechanism (not shown) which is 90 adapted to be connected with a main driving shaft 188. The heel clamps 184 are so arranged on the carrier disk 180 and certain of them are so actuated relatively to the carrier disk during the rotation of the latter that the heels are successively presented to the heel press 20 at the loading station 24 in position to be loaded into the press in accordance with the method of advantageously stacking wedge heels described in the 100 above-mentioned Hadaway application, Serial No. 258,722.

As set forth in said Hadaway application, the method of stacking heels contemplates the arrangement of the heels so that the top lift face of each heel is opposed to and covered by the top lift face of the next, and the larger base face of each heel is opposed to and covered by the adjacent large base 105 face of the next heel, base to base contacting heels being turned 180° to bring about this result. In stacking heels in accordance with this method, the heels are successively positioned at a loading station, adjacent the receiving end of the press, in the positions 110 indicated at A, B, C and D, respectively, in Fig. 16, and the heels are introduced separately, as thus positioned, into the press in the order in which they are lettered in said figure. When stacked, the heels are arranged in repeated series, each consisting of 115 four heels assembled in the relative positions indicated in Fig. 16.

In order that this method of stacking heels may be utilized in connection with a 125 multiple tube heel press so that all the heels will be subjected to the same operating conditions, the present invention contemplates the provision in the press of a number of individual press tubes or sections which is one 130

greater than the number of positions in which the heels are to be loaded, or any multiple thereof. As shown, five press tubes or sections are employed in the present machine, and these tubes are successively brought into position at the loading station 24 to receive the heels. After each heel has been preliminarily positioned at the loading station 24 in the manner described in the preceding paragraph, a horizontally reciprocating plunger 190 (Fig. 1) is employed to automatically load the heels, one at a time and progressively, into the several press tubes or sections 22, as the latter are successively positioned at the loading station with their receiving ends opposite said loading plunger. After the delivery to one of the press tubes 22 of each successive heel, the heel press 20 is rotated one-fifth of a revolution about the axis of the shaft 50 to bring the next press tube into heel-receiving position so that the heels successively delivered by the loading plunger will be loaded successively into the several press tubes 25 in rotation, one heel to each tube.

The manner in which the heels are stacked in the several tubes of the present heel press will be best understood by reference to Figs. 16 and 17, in which the reference letters A, B, C and D indicate respectively the four positions in which the heels are initially delivered by the loading mechanism 26 and are subsequently stacked in the press tubes. In Fig. 17 the five press tubes are diagrammatically illustrated and are designated by the reference numerals 1 to 5, inclusive. It is to be understood that the press tubes are rotated, step-by-step, in the direction of the arrow α , and tubes moving through one-fifth of a revolution at each step, so that they are successively positioned at the loading station 24, where properly positioned heels are loaded from the carrier 180 into the left end of the tubes by the loading plunger 190, the stack of heels in each tube being made to progress from left to right as successive heels are added to the stack at the loading station. The first heel to be loaded into the heel press is introduced in position A into tube 1, while said tube is positioned at the loading station 24. The second heel is loaded in position B into tube 2; the third heel is loaded in position C into tube 3; and the fourth heel is loaded in position D into tube 4, as said tubes are successively positioned at the loading station. One complete series of four heels, having been thus loaded into the press, the next heel of the succeeding series will be presented at the loading station in position A and will be loaded into tube 5. The next partial rotation of the heel press will bring tube 1 into heel receiving position at the loading station, and the next heel will be loaded into said tube in position B. A heel,

in position C, will next be loaded into tube 2; another heel, in position D, will be loaded into tube 3; and so on. It will be apparent, from an examination of Fig. 17, that as the heels are loaded progressively into the several tubes of the heel press in the above described predetermined order of dissimilar positions, the heels loaded into each individual tube will be stacked therein in the order and arrangement in which they were separately and successively delivered to the several tubes. By loading the heels progressively into the five press tubes in the manner described, it will be seen that so long as the press is in operation, the heels in all of the press tubes will receive regularly delivered pressure impulses as the fresh heels are successively loaded into the tubes. Consequently, after the tubes have once been filled with heels, all the heels subsequently loaded therein will be subjected to exactly the same operating conditions. As a result, all of the heels will be evenly and uniformly pressed when finally discharged from the press, and a uniform product is thus assured.

In order that the five heel press tubes or sections 22, which constitute the heel press 20, may be successively positioned to receive a heel from the loading mechanism, the heel press 20 is rotated about the axis of the shaft 50, step-by-step, in time with the carrier disk 180. The heel press is driven from the carrier disk shaft 182 by means of a sprocket chain 192 (Figs. 1 and 2) which passes over a sprocket wheel 194 on said shaft and over a sprocket wheel 196 on the shaft 50. The two sprocket wheels 194 and 196 are so proportioned as to cause the press to rotate through one-fifth of a revolution for each quarter revolution of the carrier.

To insure that the press tubes 22 will be properly positioned to receive a heel when they come to rest opposite the loading station 24, two idler sprocket wheels 198 are provided which take up the slackness of the chain and are adapted to be adjusted to cause a certain amount of rotation of the heel press 20 independently of the carrier disk 180 for the purpose of locating the press tubes with their receiving ends in the proper relation to the heel clamp 184 at the loading station. To this end the sprocket wheels 198 are severally mounted upon the upper ends of a pair of arms 200 rising from sleeves 202 which are mounted to turn on studs 204 projecting forwardly from the plate 52 upon opposite sides of the shaft 50. The arms 200 are adapted to be swung toward or from each other about the studs 204 to adjust the location of the idler sprockets 198 relatively to the sprockets 194 and 196 by means of adjusting bolts 206 which severally extend through lugs 208

projecting upwardly from the sleeves 202. The lower ends of the bolts 206 engage the upper face of the bearing on the plate 52 in which the shaft 50 is journaled. By 5 turning the adjusting bolts 206, both arms 200 may be adjusted radially in the same direction to move the idler sprocket wheels 198 toward one side or the other of the machine, and thus cause the required amount 10 of rotation of the heel press independently of the carrier disk 180 which is necessary to cause the heel guides to be properly positioned at the loading station 24. The adjusting bolts 208 are provided with nuts 210 which may be tightened against the upper faces of the lugs 208 to bind the bolts in adjusted position.

As already stated, the heel clamps 184 of the loading mechanism 26 differ from those 20 disclosed in applicant's co-pending application, and are illustrated in detail in Figs. 13, 14 and 15. The improved clamps, in common with the clamps disclosed in said application, are arranged to permit the heels 25 to be inserted therein, top lift face foremost, by movement at right angles to the plane of the carrier disk 180, and to permit the removal of the heel by a further movement in the same direction as they were introduced. In accordance with the present construction, however, the improved clamps are especially designed to firmly hold the heels 30 during the rotation of the carrier disk 180. To this end, as shown in the aforesaid figures, each heel clamp 184 comprises a pair 35 of opposed grippers 214 which are constructed and arranged to conform to the opposite lateral edges of the heels throughout a substantial portion of the height and length of the heel. To permit the grippers 214 to readily adjust themselves to the heels as the latter are introduced between them, the grippers are severally secured to a pair 40 of opposed supporting arms 216 consisting of blade-like members, each of which is pivoted at its inner extremity to a plate 217 that is riveted to the opposed webs of a pair 45 of angle iron supports 218 so that the supporting arms 216 will be capable of swinging toward and from each other. Throughout 50 a greater portion of their length the supporting arms 216 are twisted out of the plane of their hinged extremities so as to conform to the contour of the outer faces 55 of the grippers 214 and to position the grippers so that they will properly engage the lateral edges of the heel. The angle iron supports 218 are arranged with one web of each support located in the same plane and 60 extending toward the corresponding web of the other support, and these webs are adjustably clamped between a plate 220 and a clamp support 222 by means of a pair of screws 224 which extend through the plate 65 220 and also serve to secure the plate to the

support. The plate 220 and the clamp support 222 are the same as corresponding parts shown in the machine of said co-pending application, Serial No. 314,219. The gripper supporting arms 216 are yieldingly 70 pressed toward one another by means of a pair of springs 228 to cause the grippers 214 to firmly grip the heel. The springs 228 are severally coiled about a pair of supporting bolts 230 which extend outwardly 75 through the opposed webs of the angle iron supports 218 and through the inner ends of the supporting arms 216, each spring being confined between said arms and a nut 232 upon the outer end of the respective 80 bolts 230. The inward movement of the gripper supporting arms 216 under the influence of the springs 228 is limited by the engagement of the arms with the heads of the rivets which secure the plates 217 to the 85 angle iron supports 218. The nuts 232 may be adjusted on the bolts 230 to vary the tension of the spring 228 and the nuts are held in adjusted position by means of lock-nuts 234. It will be seen that by virtue of the 90 provision for yieldingly pressing the supporting arms 216 toward each other, the grippers 214 are permitted to readily adjust themselves to the contour of the lateral edges of the heels, and are caused to securely 95 hold the heels while they are being transferred.

It is desirable to securely hold the end-most heels at the receiving ends of the individual press tubes 22 so that there will be 100 no tendency for these heels to fall out of these tubes as the press is rotated. Therefore, according to the present invention each heel press tube 22 is provided with a heel-retaining device comprising a pair of clamping 105 jaws 240 (Figs. 4 and 5) which project inwardly beyond the ends of the side walls 58 and 60, at the receiving end of the press section and into the path of the heels as 110 they are loaded therein. As shown, the side walls are made somewhat shorter than the side walls 62 and 64 to permit the clamping jaws to be thus arranged without projecting beyond the receiving end of the heel press section. The clamping jaws 240 are 115 carried at the free ends of a pair of clamp arms 242, the opposite ends of which are severally pivotally mounted by pins 244 upon brackets 246 that are secured to the outer faces of the respective side walls. The 120 clamp arms 242 are pressed inwardly by means of springs 248, each of which surrounds a bolt 250 that projects outwardly from the adjacent side wall and extends through the clamp arm, the spring being 125 interposed between the outer face of the clamp arm and a nut 252 which is threaded upon the outer end of the bolt 250 and may be turned to vary the tension of the spring. The heels are engaged along a line parallel 130

to their top lift faces by means of opposed edges 254 on the clamping jaws 240, these edges being formed at the junction of two inclined faces 256 and 258 that are formed at the inner ends of each clamping jaw. By means of the inclined faces 256 the clamping jaws 240 are readily spread apart by each heel as it is discharged from the heel clamp of the carrier disk 180 at the 10 loading station 24 to permit the heel to enter the heel press section. The clamping jaws 240 are particularly useful for retaining in the press tubes those heels which are loaded therein in the position of the heel which is 15 indicated at 260 in Fig. 4.

After the automatic loading device 26 has been in operation long enough to fill the several press tubes of the heel press, a single heel is forced out or discharged from the 20 delivery end of the uppermost press 22 each time a fresh heel is introduced at the receiving end thereof by the loading plunger 190 of the loading device. As the heels are thus discharged from the delivery ends of the 25 presses, they are delivered to the unloading device 28 whereby the variously positioned heels are restored to uniform or similar positions and delivered to the platform 32. The unloading device 28 is provided with 30 four heel clamps which are of the improved construction hereinbefore described in connection with the loading device 26. With the exception of these heel clamps, the unloading device 28 is substantially the same 35 in construction and mode of operation as the corresponding mechanism disclosed in applicant's application, Serial No. 314,219, and therefore need not be herein described in detail. Briefly, however, the unloading mechanism 28 comprises a carrier disk 262 (Figs. 1 and 7), which is similar to the carrier disk 180 of the loading mechanism 26 and is secured to a sleeve 264 that is rotatable upon the shaft 182. The unloading 40 carrier disk 262 is provided with four heel clamps 266 which are the same in construction as those already described in connection with the loading mechanism 26. By the rotation of the carrier disk 264, the 45 clamps 266 are successively brought into position to receive the dissimilarly positioned heels as they emerge from the heel presses, and are actuated to restore these variously positioned heels to uniform or similar positions, and to bring them to rest at a point 50 opposite the transfer station 34. The heels are discharged from the clamps 266 of the carrier disk 262 of the unloading device and delivered upon the platform 32 by means of 55 a horizontally reciprocating plunger 268, which operates in unison with the loading plunger 190 in the same manner as in applicant's co-pending application already referred to.

60 As explained in applicant's hereinbefore

mentioned co-pending application, the length of the column of heels in a press tube may vary, from time to time, on account of the fact that differences in the character of the continually changing individual heels in the column may cause some heels to compress into smaller space than others under the repeated pressure impulses of the loading plunger. As a result, it is possible that the heel at the forward end of the column may not be advanced clear of the delivery end of the press tube each time a fresh heel is loaded into the receiving end of the tube. In such a case, while the rear portion of the end heel still remains within the press tube, the forward portion of said heel will project between the jaws of the adjacent heel clamp on the unloading carrier 262, thus preventing said carrier from making its next partial rotation which is to carry the heel toward the unloading plunger 268. In accordance with the present invention, provision is made for insuring that the end heel in each press tube shall be completely ejected from the tube each time a fresh heel is introduced into the receiving end of the tube. To this end, in the present construction, the unloading carrier 262 is normally disconnected from the shaft 182 upon which it is mounted and is arranged to be connected therewith by means of a clutch 270, (Fig. 1) the operation of which is controlled by the feeding movements of the heel at the delivery end of the heel press. This is accomplished by the employment of mechanism which is substantially the same as that employed for the same purpose in the machine of applicant's above mentioned application. This mechanism, therefore, will not be described in detail herein, inasmuch as reference may be had to said application for a complete description, if desired.

Briefly, however, in common with the machine of the application just referred to, the sleeve 264 (Figs. 1 and 7) upon which the unloading carrier 262 is mounted, is journaled in bearing sleeves 272 and 274, on opposite sides of the carrier, the sleeves 272 and 274 being splined in guideways formed respectively in the standards 44 and 46. This construction permits lateral sliding movements of the carrier 262 toward and from the heel press. The unloading carrier 262 is moved bodily away from the press by the advance of each heel as it is fed between the jaws of the respective heel clamp on said carrier, and into engagement with an abutment 276 (Fig. 7) which is mounted to slide with said carrier. The sliding movement of the carrier 262 operates the clutch 270 to connect the unloading carrier with the shaft 182 so that said carrier will be rotated in unison with the loading carrier 180 when the next movement of the latter occurs. At the start of

the rotation of the unloading carrier 262, the abutment 276 is quickly withdrawn from the path of rotation of the heel clamps and the carrier is locked in the plane to which it was laterally moved by the last feed movement of the heels in the heel press, by means of mechanism controlled by a cam 278, all as set forth in applicant's co-pending application.

10 As further set forth in said application, the heels in the press are liable to adhere to each other more or less on account of the accidental presence of paste on the tread or base faces of the heels or on the sides of the press. Accordingly in order to insure that the heel which is delivered to the unloading carrier shall be readily separated from the column of heels in the press tube, without the possibility of laterally displacing the adjacent heel, the following improved means, particularly adapted for the multi-press structure of the present machine, is provided for laterally supporting the projecting portion of the heel next behind the end heel in the stack in each press tube, after the end heel has been pushed beyond the end of the press tube.

This improved means comprises a plurality of pairs of flat plates 282 (Figs. 7, 11 and 12) which are associated with the delivery ends of the side walls 58 and 60 of the several press tubes 22. These plates 282 are similar in their general mode of operation to the corresponding plates of applicant's hereinbefore mentioned application, but are modified in the present construction as found necessary to adapt them for use in a multiple tube heel press. As shown, the plates 282 are carried by and are movable with the rotatable support for the heel press and serve to extend the side walls of each press tube toward the unloading carrier as soon as the end heel engages the abutment 276 and begins to move the carrier laterally away from the heel press. Each pair of plates 282 is arranged with its individual members extending in parallel relation on opposite sides of the side wall 64 of the respective press tube, each plate projecting outwardly from one of a series of supports 284 which are arranged equi-distant from each other and from the shaft 50 and are slidably mounted upon a carrier 286 which is secured to said shaft. The side walls 58 and 60 of the press tubes are cut away at the delivery end of the press to permit the plates 282 to be arranged with their opposed faces flush with the inner faces of said walls.

60 To permit the plates 282 to move laterally toward and from each other as the side walls of the heel guide are moved inwardly or outwardly, these plates are mounted to slide upon the opposite ends of a pair of parallel guide rods 294 which extend in a

direction normal to the length of the heel guides, and the central portions of which are secured to an ear 296 projecting from the support 284. In order that the opposed members of each pair of plates 282 shall be constrained to move laterally with the side walls 58 and 60, each plate 282 is provided with an outwardly turned ear 288 which extends across the end of the adjacent side wall and carries a projecting pin 290 which is slidably received in a socket 292 that is bored longitudinally into said side wall from the end thereof. This construction also permits the plates 282 to move edgewise in the direction of the length of the press tube in order to extend the side walls 58 and 60 for the purpose described.

To cause the plates 282 to be moved edgewise in the direction of the length of the heel guides, for the purpose of extending the side walls 58 and 60 thereof, the supports 284 are caused to slide longitudinally with respect to the carrier 286. To permit such sliding movement, each support 284 is provided with a pair of end lugs 298 through which extend a pair of parallel horizontal rods 300 which are rigidly secured thereto. Adjacent their opposite ends, the rods 300 extend through and are adapted to slide in guideways 302 which are formed in the flanged ends 304 of the carrier 286.

Normally each pair of plates 282 is held retracted, in the positions in which they appear in Figure 11, by means of a pair of coiled springs 306 which severally surround the rods 300, the springs being interposed between the inner face of one of the flanged ends 304 of the carrier 286 and a shoulder 308 on the support 284. The supports 284 are caused to slide relatively to the carrier 286 to advance the plates 282 edgewise toward the unloading carrier for the purpose of extending the side walls of the press tubes by means of an actuator sleeve 310 which is adapted to slide on the shaft 50, adjacent one end of the carrier 286. The actuator sleeve 310 is provided with an upwardly projecting lug 312 that is adapted to engage depending lugs 314 on the several supports 284, as the respective heel guides are brought into position for the delivery of a heel to the unloading carrier 262. Movement of the actuator sleeve 310 is effected by means of a rod 316, one end of which is rigidly secured to a lug 318 projecting laterally from the actuator sleeve 310, and which connects said sleeve with a movable bracket 320. This bracket 320 is secured to the bearing sleeve 274 of the unloading carrier 262 and moves laterally toward and from the heel press therewith.

The operation of the mechanism just described is as follows: When one of the press tubes is brought to rest in position to receive

a fresh heel and discharge a dried heel, the support 284, carrying the plates 282 which are associated with said press tube guide, will be positioned with its lug 314 opposite 5 the lug 312 on the actuator sleeve 310, as shown in Fig. 7. When the end heel is forced out of the heel guide into engagement with the abutment 276 and the unloading carrier 262 begins to be moved laterally 10 away from the heel press, the actuator sleeve 310 will be actuated through the connections above described to slide the support 284 which is associated with the uppermost heel guide toward the delivery end thereof. Thus, 15 the plates 282 carried thereby are actuated to extend the side walls 58 and 60 of said press tube. In this way, if the heel next behind the end heel of the stack is projected beyond the end of the heel guide, the projecting portion 20 of said heel will be laterally supported by the plates 282, and when the unloading carrier 262 makes its next partial rotation this heel, which is between the plates, will be effectively retained against any tendency to 25 be moved edgewise by the rotation of the carrier and consequently the heel which has just been delivered to the carrier will be readily separated from the stack.

As the unloading carrier 262 approaches 30 the completion of its quarter revolution, the mechanism which is controlled by the cam 278 operates in the manner set forth in applicant's co-pending application, to restore the abutment 276 to its 35 normal position and operate the clutch 270 to disconnect the unloading carrier. The carrier is then free to slide laterally toward the heel press. In the present construction, the unloading carrier 262 is moved 40 laterally toward the press by means of a spring 322 (Figs. 1 and 7), the lower end of which is secured to the base 40 and the upper end of which is connected to one arm of a bell-crank lever 324 which is pivoted at 326 45 upon the standard 46, the other arm of the lever being connected by a link 328 to the movable bracket 320.

In common with the corresponding mechanism described in applicant's hereinbefore 50 mentioned application, the unloading mechanism 28 of the present machine, after having received the variously positioned heels emerging from the heel press, restores these heels to the uniform positions in which they 55 were initially presented to the loading mechanism 26. This position of the heels is indicated by dotted lines in Fig. 7. As therein shown, the heel is positioned with its breast edge upon the platform 32 and 60 with its base face directed toward the unloading plunger 268.

After the unloading carrier 262 has been returned to its normal lateral position, the unloading plunger 268 is actuated, as explained in applicant's above mentioned co-

pending application, to eject the heel from the uppermost heel clamp in the carrier and deliver it to the platform 32. As also set forth in said application, the platform 32 is secured to a member 330 which is, in turn, 70 secured to the bearing sleeve 274, so that the platform will move with the carrier 262 as the latter is shifted laterally. To insure that the heel will be deposited upon the platform 32 in exactly the position in which it is 75 held by the heel clamp immediately before it is ejected from the unloading carrier 262, means is provided, in accordance with the present invention, for maintaining control of the heel during its transfer from the unloading carrier to the platform 32.

In the present construction, the means for thus controlling the movement of the heel, from the unloading carrier 262 to the platform 32, comprises a vertically disposed 85 presser plate 336 that is arranged to engage the top-lift face of the heel and to cooperate with the unloading plunger 268 to laterally support the heel as the plunger feeds it across the platform 32. The presser plate 336 is disposed in parallel relation to the carrier disk 262 and is normally located in position to be engaged by the tread face of the heel as the heel leaves the clamp in said carrier disk. As shown in Fig. 8, the presser plate 336 is laterally offset from a horizontal tube 338, to one end of which the plate is rigidly secured. A deep notch 337 (Fig. 8) is provided in the plate 336 to permit the engagement with the heel of a positioning finger hereinafter to be described. The opposite end of the tube 338 is received in a bearing sleeve 340 (Fig. 7) in which the tube is adapted to slide. The bearing sleeve 340 is rigidly secured in the unloading carrier. 100 The horizontal tube 338 is urged toward the left (Fig. 7) by means of a coiled spring 342 which is confined within the tube 338 and bearing sleeve 340, the opposite ends of the spring engaging the closed ends of the tube 105 and bearing sleeve. The normal position of the presser plate 336 is determined by an adjustable bolt 344 which extends through a lug depending from a portion of the presser plate. The bolt 344 is adapted to engage a stop lug 346 on the platform 32, the lug limiting the movement of the presser plate under the influence of the spring 342. By means of this construction the heels are 115 firmly held between the unloading plunger 268 and the presser plate 336 during their transfer from the unloading carrier to the platform 32, so that there will be no tendency for the heels to be displaced from the positions they occupied when brought opposite the unloading plunger by the carrier 262.

After the heels are delivered to the platform 32 in the manner described, the present invention makes provision for them to be transferred to a heel compressor by means 120

of the conveyor 38 which travels toward the observer when viewing Fig. 7. In order that the heels may be transferred to the compressor without danger of being displaced from the positions in which they are deposited upon the conveyor, it is desirable that the heels should rest upon their base lifts upon the conveyor. It is further desirable that the heels should be arranged upon the conveyor with their breast edges 10 earmost, in order that they may be in proper position to be fed to the heel compressor, the latter being preferably of the type disclosed in United States Letters Patent No. 1,213,052, granted January 16, 1917, to E. E. Winkley, and assigned to the United Shoe Machinery Corporation.

Accordingly one of the features of the present invention resides in the transfer mechanism 36 by means of which the heels are removed from the platform 32 and deposited upon the conveyor 38 in the requisite positions just described. The transfer mechanism 36 (Figs. 1, 7, 8, 9 and 10) comprises a rotary transfer carrier 350 upon which are mounted three sets of heel gripping devices 352. The heel gripping devices 352 are mounted upon three angularly disposed arms 353 which are equi-distant from each other and which are inclined at an angle of 45° with respect to the axis of rotation of the transfer carrier. Normally, the transfer carrier 350 is maintained stationary with one of its three heel gripping devices located immediately above the platform 32 in readiness to receive a heel, while another of said gripping devices is located immediately above the conveyor 38, having deposited its heel upon the conveyor. Throughout the operation of the machine, the transfer carrier 350 is rotated step-by-step in time with the rotary movements of the loading and unloading carriers 180 and 262, the transfer carrier making one-third of a revolution for each one-quarter revolution of the other carriers. Each heel gripping device 352 of the transfer mechanism 36 comprises a pair of articulated gripper jaws 354 which are spring-actuated to grip the heels and are positively actuated to release them. Concurrently with each partial rotation of the loading and unloading carriers the transfer carrier 350 is rotated through 120° to bring one set of heel gripping devices 352 into position to grip a heel on the platform and then into position to deposit its heel in the requisite position upon the conveyor 38. The transfer carrier 350 is secured to the lower end of an inclined shaft 356 which is journaled in a bearing 358 at the upper end of the standard 46. Pinned to the upper end of the shaft 356 is a bevel gear 360, the hub of which, by engagement with the upper end of the bearing 358, sustains the weight 60 of the transfer carrier 350 and retains the

shaft 356 in its bearing. The shaft 356 is inclined upwardly at an angle of 45° with respect to the platform 32, and it is also inclined, transversely of the machine, at an angle of 45° with respect to a vertical plane 70 extending through the axis of the shaft 50.

The three heel gripping devices 352 are identical, and consequently it will be necessary to describe but one of them in detail. The gripper jaws 354 are best shown in Figs. 8 to 10, and are provided with sharply pointed ends for engaging the opposite lateral edges of the heels. Each gripper jaw 354 is secured to one end of a shaft 364, the shafts 364 for each pair of gripper jaws being journaled in bearings 366 carried by webs 368 which project from opposite sides of the inclined arms 353 of the transfer carrier 350. The opposite ends of the shafts 364 project beyond the bearings 366 80 and to each projecting end is secured a gear segment 370, the two segments 370 intermeshing as shown in Fig. 9. The gear segments 370 are connected by means of a coiled spring 372, the opposite ends of which are secured to a pair of arms 374 which project substantially at right angles to the segments 370 so that each segment 370, together with its projecting arm 374, constitutes a bell-crank lever. Each pair of heel gripper jaws 354 is normally held in open or heel-receiving position by means of a latch 376 which is pivoted at 378 upon the respective transfer carrier arm 353, the free end of the latch being notched to provide a pair of 90 perpendicularly disposed shoulders 380 and 382 for engaging a stud 384 projecting upwardly from one of the adjacent gear segments 370. A spring 386, one end of which is secured to the latch 376 and the opposite end to a pin 387 on the adjacent gripper device, tends to hold the latch in operative position with the shoulder 380 engaging the stud 384 in order to hold the gripper jaws 354 out of engagement with the heel. 100 Cooperating with each pair of gripper jaws 354 to uniformly hold the heels in the position in which they are presented to the transfer mechanism is a positioning finger 388 (Figs. 7, 8 and 10) which is adapted to engage the tread face of the heel to prevent the heel from turning out of the position in which it is held by the gripper jaws as the transfer carrier 350 is rotated. The notch 337 which is provided in the presser plate 336, as hereinbefore described, permits the finger 388 to come into contact with the heel as the latter is pushed across the platform 32. Each positioning finger 388 depends from one end of a hollow cylindrical stem 390 (Fig. 10) which is received in a socket 392 in each inclined arm 353 of the transfer carrier. The stems 390 are pressed outwardly in their sockets to maintain the positioning fingers 388 in position 110 120 125 130

to be engaged by a heel which is advancing between the gripper jaws, by means of a spring 394 within the hollow stem 390, one end of the spring bearing against the 8 base of the recess in the stem and the opposite end of the spring engaging the base of the socket 392. To prevent the stem 390 from turning in its socket, and thus to definitely locate the positioning finger with respect to the transfer carrier, a pin 396 projects from the side of the stem 390 into a longitudinal slot 398 which is formed in the wall of the socket 392. The pin 396 is adapted to engage one end wall of the slot to 15 limit the movement of the positioning finger under the influence of the spring.

To effect the transfer of the heels from the platform 32 to the conveyor 38, the transfer carrier 350 is driven from the shaft 182. 20 To this end the shaft 356, upon which the transfer carrier is mounted, is connected with an intermediate horizontal shaft 402 by means of intermeshing bevel gearing comprising a gear 404 which is secured to 25 one end of the shaft 402 and the gear 360 which is secured to the upper end of the transfer carrier shaft 356. The intermediate shaft 402 is journaled in a bearing 406 at the upper end of the standard 46 and is connected with the shaft 182 by means of a 30 sprocket chain 408 (Figs. 1 and 8) which passes over a sprocket wheel 410 on the shaft 402 and over a sprocket wheel 412 at the end of the shaft 182. These sprocket 35 wheels are so proportioned that each quarter turn of the shaft 182 will cause the transfer carrier 350 to be rotated through one-third of a revolution.

The arrangement of the heel gripping devices 352 upon the transfer carrier 350 is such that when the transfer carrier comes to rest, one of the gripping devices will be positioned to receive a heel from the unloading carrier 262 while another of the gripping devices is positioned to deposit a heel upon the conveyor 38. When a heel has been advanced, by means of the unloading plunger 268, upon the platform 32 into position to be engaged by the first-mentioned 45 gripping device, the jaws of said gripping device are released to permit them to grip the heel. At the same time the jaws of the gripping device which is holding a heel above the conveyor 38, are forced apart to 50 release the heel held thereby. The means for thus actuating the two pairs of gripper jaws operates in unison with the unloading plunger 268 and comprises a horizontal slide rod 414 (Fig. 7) which is mounted in bearings 416 at the upper ends of the standards 44 and 46. The slide rod 414 is connected with the unloading plunger 268 by means of an arm 418 (Figs. 1 and 7), the upper end of which is secured to the slide rod while 55 the lower end thereof is secured to a pin 420

which projects laterally from the unloading plunger and which is engaged by the member that actuates the plunger.

To release the jaws of the heel gripping device which is ready to receive a heel at the 70 transfer station 34 so that said jaws may seize the heel, a pin 422 depends from a collar 424 which is adjustably secured to the slide rod 414 between the bearings 416. The pin 422 is adapted to engage a tail 426 (Fig. 75 9) extending perpendicularly from the pivoted end of the latch 376 to swing the latch in a direction to disengage the shoulders 380 and 382 from the stud 384 on the segment 370. Thereupon, the jaws 354 are 80 released and the interposed spring 372 actuates them into gripping relation with the heel on the platform 32.

The means for opening the jaws of the heel gripping device which is supporting a 85 heel above the conveyor 38 comprises a spring-restrained horizontal plunger 430 (Fig. 7) which is confined in a socket in the upper portion of the standard 46. One end of the plunger 430 is adapted to engage 90 a series of projections 432, one of which is formed upon one of the individual members of each pair of gear segments 370. The plunger 430 is so arranged that when 95 one of the gripper devices is located in position to discharge a heel upon the conveyor 38, the respective gear segment projection 432 will be located opposite one end of the plunger. The plunger 430 is normally held out of engagement with the projection 432 100 by means of its spring which is indicated at 434, Fig. 7. To actuate the plunger 430, a bell-crank lever 436 is pivoted at 438 to the upper portion of the standard 46, the lowermost end of said lever engaging the end 105 of the plunger 430 which is remote from the transfer carrier, while the upper end of the bell-crank lever engages an inclined cam face 440 at the rear extremity of the slide rod 414.

When the unloading plunger 268 is actuated to eject the heel from the heel clamp in the unloading carrier 262, the tread face of the heel, which is directed toward the transfer mechanism 36, is brought into engagement with the presser plate 336. As the heel is held between the unloading plunger and the presser plate 336, it continues to advance across the platform 32 and the tread face thereof finally engages the positioning finger 388 which yields sufficiently to permit a heel to be advanced to a definite position between the opened jaws of the associated gripper device. Thereupon, the pin 422 on the slide rod 414 engages the tail 426 on the respective latch 376, tripping the latch and releasing the gripper jaws so that they are closed by the force of the spring 372 upon the opposite lateral edges 110 of the heel.

Concurrently with the tripping of the latch 376 by the pin 422, the cam face 440 at the end of the slide rod 414 actuates the bell-crank lever 436 to force the plunger 430 against the projection 432 on the gear segment of the gripping device which is holding a heel above the conveyor 38, causing the jaws 354 of said device to be spread apart so that the heel will be released and deposited upon the conveyor. The gripper jaws 354 of said gripping device are held in their open positions by means of the respective latch 376 which is swung by its spring 386 to bring its shoulders 380 and 382 into engagement with the associated pin 384.

Inasmuch as the transfer carrier 350 rotates in the direction of the arrow in Fig. 7, it will require two step movements or partial rotations of said carrier to transfer a heel from the platform 32 to the conveyor 38. The gripper devices 352 being spaced 120° apart upon the transfer carrier 350, it will be seen that each heel will travel through two-thirds of a revolution, and consequently will be turned 240°, during its transfer from the platform 32 to the conveyor 38. The transfer carrier being arranged with its axis of rotation inclined in the manner hereinbefore described, the heels, after being transferred to a position of deposit above the conveyor 38, will be positioned with their base faces lowermost and with their rounded rear ends facing the direction in which the conveyor is to be advanced. Upon the opening of the gripper jaws, the heel will be deposited in this position upon the conveyor.

While the method and apparatus of the present invention have been described more or less in detail it is to be understood that the invention is not so restricted and that many of the advantages thereof may be derived from methods and machines differing considerably from those specifically described without departing from the spirit and true scope of the invention as defined in the appended claims.

Having thus described the preferred method and embodiment of the invention, that which is claimed as new is:

1. The method of assembling pieces of shoe stock which comprises arranging the pieces in repeated like series in each of which the pieces are arranged in predetermined relation, and in consecutively distributing the pieces in regular order and one at a time in stacked relation at a number of successive stations in rotation that exceeds by one the number of pieces in a series, or any multiple thereof, to progressively produce at each station a stack of pieces of stock in which the same repeated serial relation of pieces obtains.

2. The method of assembling pieces of shoe stock in repeated like series, which com-

prises arranging the pieces in predetermined relation in repeated series, and consecutively depositing said pieces in regular order, and one at a time, as fast as they are individually arranged, at a plurality of successive stations in rotation, the number of which bears such a relation to the number of pieces in a series that the relationship of the stacked pieces at each station is the same as the repeated series relation in which the pieces are successively and individually arranged. 70

3. The method of assembling pieces of shoe stock in repeated like series which comprises arranging the pieces in predetermined relation in repeated series, and consecutively depositing said pieces in regular order and one at a time as fast as they are individually arranged at a plurality of successive stations in rotation exceeding in number by one the number of pieces in each series, or any multiple thereof, to produce at each station repeated like series in each of which the relation of pieces corresponds to the relation in which the pieces were individually and successively arranged before being distributed. 80

4. The method of assembling pieces of shoe stock comprising arranging the pieces consecutively in repeated like series with each piece of each series occupying a predetermined dissimilar relative position, and in consecutively and progressively distributing said pieces one at a time, as fast as they are separately and successively thus positioned, at a number of receiving stations in rotation which exceeds by one the number of pieces in a series, or any multiple thereof, to produce at each station repeated similar series of pieces. 90

5. The method of assembling similarly shaped heels which comprises arranging the heels in repeated like series, each comprising a predetermined number of heels arranged in predetermined dissimilar relative positions, and in consecutively distributing the heels one at a time and in the same order and positions at a number of successive stations in rotation that exceeds by one the number of heels in a series, or any multiple thereof, whereby a stack of heels is produced at each station in which the heels occupy the same series arrangement. 105

6. The method of assembling similarly shaped wedge heels which comprises arranging the heels in repeated like series, each comprising four heels arranged in predetermined dissimilar relative positions, and in consecutively distributing the heels one at a time and in the same order and positions at five successive receiving stations in rotation whereby a stack of heels is produced at each station in which the heels occupy the same series arrangement as they occupied before being distributed. 110

7. The method of pressing similarly shaped wedge heels arranged in repeated like series of four heels each in the press tubes of a multi-unit heel press having one more press tube than there are heels in a series or any multiple thereof, which method comprises definitely positioning the heels in repeated series of four in predetermined dissimilar relative positions, and, as fast as the heels are successively positioned, loading them singly and in regular order into the several successive press tubes in rotation to produce in each tube a straight row of heels arranged in repeated like series, each corresponding in relationship to the initial four heel serial arrangement.

8. A machine for assembling pieces of shoe stock having, in combination, a plurality of tube-like presses through which the pieces of stock are advanced in stack formation and severally adapted to frictionally resist the passage of the stock therethrough, and means for supporting the presses and bringing them successively to a common loading position to receive the stock.

9. A machine for assembling pieces of shoe stock having, in combination, a plurality of tube-like presses through which the pieces of stock are advanced in stack formation, and severally adapted to frictionally resist the passage of the stock therethrough, and a rotatable support upon which the presses are so arranged as to be brought successively to a common loading position by the rotation of said support.

10. A machine for assembling pieces of shoe stock having, in combination, a plurality of tube-like presses through which the pieces of stock are advanced in stack formation and severally adapted to frictionally resist the passage of the stock therethrough, a rotatable support upon which the presses are mounted, and means for rotating said support to bring the presses successively to a common loading position to receive the stock.

11. A machine for assembling pieces of shoe stock having, in combination, a plurality of tube-like presses through which the pieces of stock are advanced in stack formation and severally adapted to frictionally resist the passage of the stock therethrough, a rotatable support on which the presses are mounted, means for rotating said support to bring the presses successively to a common loading position to receive the stock, and means for loading the stock into the receptacles.

12. A machine for assembling pieces of shoe stock having, in combination, a plurality of receptacles for holding the pieces of stock, means for supporting the receptacles and bringing them repeatedly to a common loading position, in regular order and means for loading a single piece of stock into each

receptacle each time it is brought to said loading position.

13. A machine for assembling pieces of shoe stock having, in combination, positioning means for receiving similarly positioned pieces of stock and presenting them in succession and in dissimilar positions at a loading station, a plurality of receptacles for holding the stock, means for supporting the receptacles and bringing them successively into position at the loading station to receive the stock, and means for loading the stock into the receptacles in the positions presented at the loading station.

14. A machine for assembling pieces of shoe stock having, in combination, positioning means for receiving similarly positioned pieces of stock and presenting them in succession and in different relative positions at a loading station, a rotatable support, a plurality of receptacles mounted on the support for holding the stock, means operating upon the differently positioned pieces of stock at the loading station to load them into said receptacles, and means operating in timed relation with said loading means for intermittently rotating said support to position the receptacles to progressively receive the pieces of stock.

15. A machine for assembling pieces of shoe stock having, in combination, means for receiving similarly positioned pieces of stock and delivering them successively in repeated like series with successive pieces of each series in different relative positions, and a plurality of receptacles successively positioned to receive the stock as delivered, one piece of stock to each receptacle, the number of the receptacles being such that the sequence of positions of the pieces of stock in each receptacle will be the same as the sequence of positions of the pieces as delivered by said first means.

16. A machine for assembling pieces of shoe stock having, in combination, positioning means for receiving similarly positioned pieces of stock and presenting them successively at a loading station in repeated like series with successive pieces of each series in different relative positions, a plurality of receptacles successively positioned to receive the stock as delivered, one piece of stock to each receptacle, the number of receptacles being such that the sequence of positions of the pieces of stock in each receptacle will be the same as the sequence of positions of the pieces as delivered by said positioning means, and means operating upon the pieces of stock successively presented at the loading station to load said pieces into the receptacles.

17. A machine for assembling pieces of shoe stock having, in combination, means for receiving similarly positioned pieces of stock and delivering them successively in

- repeated like series with successive pieces of each series in different relative positions, and a plurality of receptacles successively positioned to receive the stock as delivered, one 5 piece of stock to each receptacle, the number of the receptacles being one greater than the number of positions in which the pieces of stock are delivered, or any multiple of said positions, so that the sequence of positions of 10 said pieces in each receptacle will be the same as the sequence of positions of the pieces as delivered by said first means.
18. A machine for assembling pieces of shoe stock having, in combination, positioning means for receiving similarly positioned pieces of stock and presenting them successively at a loading station in repeated like series with successive pieces of each series in different relative positions, a plurality 15 of receptacles successively positioned to receive the stock as presented at the loading station, one piece of stock to each receptacle, the number of the receptacles being one greater than the number of positions 20 in which the pieces of stock are presented, or any multiple of said positions, so that the sequence of positions of said pieces in each receptacle will be the same as the sequence of positions of the pieces as presented by said positioning means, and means operating upon the pieces of stock successively presented at the loading station to load said pieces into the receptacles.
19. A machine for assembling pieces of shoe stock having, in combination, a positioning device for receiving pieces of stock presented thereto in similar positions and arranging them successively in repeated like 25 series of predetermined dissimilar positions 40 at a loading station, a plurality of tube-like receptacles through which the stock is advanced in stack formation, means for supporting said receptacles and moving them successively into position to receive the stock 45 at the loading station, and means operating upon the pieces of stock dissimilarly positioned at the loading station to introduce them into said receptacles as the latter are successively positioned at said station 50 and to cause the pieces of stock previously introduced into said receptacles to be advanced therein.
20. A machine for operating upon heels having, in combination, positioning means 55 for receiving similarly positioned heels and presenting them successively at a loading station in repeated like series of four heels each with successive heels of each series in different relative positions, a heel holding 60 device comprising a rotatable support and five tube-like heel presses mounted upon said support through which the heels are advanced in stack formation and severally constructed and arranged to frictionally resist the passage of the heels therethrough,
- means for rotating said support to successively position the presses to receive the heels as presented at the loading station, and means operating upon the heels successively presented at the loading station to load them 70 progressively into the presses.
21. A machine for operating upon heels having, in combination, a rotatable support, a plurality of tube-like presses mounted upon said support through which freshly pasted heels are made to progress in column formation against the frictional resistance of the sides of the presses, a rotary carrier having a plurality of heel clamps for receiving the heels, means for rotating the carrier step-by-step to bring the heel clamps successively to a loading station, means for rotating said support in time with the carrier to bring the presses successively to the loading station 75 opposite one of the heel clamps, and means 80 for transferring the heels from the clamps to the presses at the loading station.
22. A machine for operating upon heels having, in combination, a rotatable support, a plurality of tube-like presses mounted upon said support through which freshly pasted heels are made to progress in column formation against the frictional resistance of the sides of the presses, a loading mechanism comprising a rotary carrier having a plurality of heel clamps for holding the heels, means for rotating the carrier step-by-step to bring the heel clamps successively to a loading station, means for rotating said support in time with the carrier to 90 bring the presses successively to the loading station opposite one of the heel clamps, means for transferring the heels from the clamps to the presses at the loading station, and means for imparting a partial rotation 95 to the support independently of the carrier to adjust the location of the presses relatively to the heel clamps for the purpose of bringing them exactly opposite each other.
23. A tube-like heel press comprising four longitudinal side members arranged in oppositely disposed pairs and supported with provision for relative adjustment at a plurality of points throughout their length, and means for effecting simultaneous adjustment of the members of each pair independently of the members of the other pair to adjust the press to heels of different sizes or proportions.
24. A tube-like heel press comprising four longitudinal side members arranged in oppositely disposed pairs, means for separately imparting simultaneous movements to the members of each pair to adjust the press to operate on heels of different sizes or proportions, and means permitting each pair of side members to yield outwardly independently of the other pair of side members to permit the press to automatically ad- 125 130

just itself to differently proportioned heels of the same size.

25. A heel press having, in combination, a rotatable support, a plurality of tube-like structures carried by the support, each comprising a plurality of longitudinal side members supported with provision for relative adjustment at a plurality of points throughout their length, and means for feeding heels 10 to said tube-like structures.

26. A heel press having, in combination, a rotatable support, a plurality of tube-like structures carried by the support, each having a pair of longitudinal side members supported with provision for relative adjustment at a plurality of points throughout their length, and means for effecting simultaneous adjustment of the side members.

27. A heel press having, in combination, a rotatable support, a plurality of tube-like structures carried by said support, each comprising four longitudinal side members arranged in oppositely disposed pairs, and means for effecting relative adjustment of 25 the individual members of one pair in each of said structures independently of the other pair of side members.

28. A tube-like heel press comprising four longitudinal side members arranged in oppositely disposed pairs, a plurality of arms pivotally connected with the side members for supporting the same and movable to adjust the opposite side members toward or from each other to vary the size of the press, 35 and means for maintaining the adjacent side members in perpendicular relation.

29. A tube-like heel press comprising four longitudinal side members arranged in oppositely disposed pairs each side member 40 having a guideway extending transversely therein from one longitudinal edge thereof, a plurality of arms pivotally connected with the side members for supporting the same and movable to adjust the opposite side 45 members toward or from each other to vary the size of the press, and means comprising an angle member having two arms disposed at right angles to each other and adapted to slide in the guideways of adjacent side members for maintaining said side members in 50 perpendicular relation.

30. A heel press having, in combination, a close-fitting tube-like structure adapted to receive heels successively at one end thereof 55 and having yielding walls to resist frictionally the passage of the heels therethrough, and means at the receiving end of said structure and entered through opposed sides thereof for engaging the endmost heel there- 60 in to retain it within the structure.

31. A tube-like heel press having, in combination, separate longitudinal side members adapted to frictionally resist the passage of the heels through the press, and a plurality 65 of inwardly pressed fingers carried by the

side members at the receiving end of the press and movable relatively to the side members for engaging opposite edges of the endmost heel to retain said heel within the press. 70

32. A heel press having, in combination, a pair of oppositely disposed longitudinal side members adapted to frictionally resist the passage of heels therebetween and a pair of outwardly yielding clamping jaws severally mounted upon said side members and movable relatively thereto for engaging the opposite edges of the endmost heel to retain said heel in the press, said jaws normally projecting into the path of movement of the heels and being adapted to be forced outwardly by a heel as it is introduced into the press. 75

33. A machine for operating upon heels having, in combination, a positioning device for receiving uniformly positioned heels and arranging them successively in repeated like series of predetermined dissimilar positions at a loading station, a rotatable support, a plurality of tube-like heel presses mounted upon said support through which the heels are advanced in stacked formation, and severally constructed and arranged to frictionally resist the passage of the heels therethrough, means for rotating the support to bring the presses successively into position to receive a heel at a loading station, means operating upon the heels dissimilarly positioned at the loading station to introduce them into the presses as the presses are successively positioned to receive the heels and to cause the heels previously loaded into the presses to be forced therethrough and finally discharged therefrom, and a second positioning device for receiving the heels as they are successively discharged in dissimilar positions from the presses and restoring the heels to uniform positions. 90 95 100

34. A machine for operating upon heels having, in combination, a positioning device for receiving uniformly positioned heels and arranging them successively in repeated like series of predetermined dissimilar positions at a loading station, a rotatable support, a plurality of tube-like heel presses mounted upon said support through which the heels are advanced in stacked formation, and severally adapted to frictionally resist the passage of the heels therethrough, the 105

number of the presses being one greater than the number of positions in which the heels are arranged by said positioning means, means for rotating the support to bring the presses successively into position to receive a heel from said positioning device at a loading station, and means operating upon the heels dissimilarly positioned at the loading station to introduce them into the presses, one heel to each press, as the presses are successively positioned to receive the 110 115 120 125 130

heels and to cause the heels previously loaded into the presses to be forced therethrough and finally discharged therefrom.

35. A machine for operating upon heels having, in combination, a plurality of tube-like heel presses through which the heels are advanced in stacked formation in repeated like series of dissimilarly positioned heels and severally adapted to frictionally resist the passage of the heels therethrough, means for bringing the heel presses successively into position to receive a heel at one end and to discharge a heel from the opposite end, loading means operating when each press is in said position to introduce a heel into the receiving end thereof and to cause the heels previously loaded in the press to be advanced therein and finally discharged therefrom, a positioning device for receiving the heels as discharged in dissimilar positions from the presses and rearranging the heels into similar positions, a support for receiving the heels from the positioning device, and an unloading device operating in step with the loading means for removing the similarly positioned heels from the positioning device and delivering them to said support. 70

36. A heel clamp for a heel-transferring device having, in combination, a pair of opposed gripper jaws constructed and arranged to conform to the contour of the opposite lateral edges of a heel, a pair of pivoted arms for supporting said jaws, means for yieldingly pressing said arms toward each other to cause said jaws to grip a heel placed between them to firmly hold the heel during its transfer, and means to limit inward movement of said arms, that said jaws may receive the heel between them. 80

37. A heel clamp for a heel-transferring device having, in combination, a pair of opposed gripper jaws constructed and arranged to conform to the contour of the opposite lateral edges of a heel, a pair of pivotally mounted arms to which said jaws are secured, individual springs severally arranged to press said arms inwardly to cause the jaws to grip a heel placed between them to firmly hold the heel during its transfer, and means to limit inward movement of said arms, that said jaws may receive the heel between them. 90

38. A machine for operating upon heels having, in combination, a plurality of tube-like presses through which the heels are advanced in stack formation, the presses being severally adapted to frictionally resist the passage of the heels therethrough, means for supporting the presses and bringing them successively to a common loading and unloading position in which heels may be received at one end of the press and discharged from the opposite end thereof, loading mechanism for introducing heels singly

into the receiving ends of the presses as the latter are successively positioned to receive the heels and for causing heels previously loaded into said presses to be advanced therein and finally discharged from the delivery ends thereof, means for receiving the heels as they are discharged from the presses, devices associated with the delivery end of each press for extending said press longitudinally, a common actuator for said press extending devices adapted to operatively engage said devices as said presses are successively brought into position for the reception and discharge of heels, and means for operating the actuator to cause said devices to extend the presses. 75

39. A machine for operating upon heels having, in combination, a heel press constructed and arranged to receive heels in column formation, mechanism for removing the heels from the press and delivering them at a point removed from the press, a support upon which the heels are delivered, a conveyor, and means for transferring the heels from the support to the conveyor. 85

40. A machine for operating upon heels having, in combination, a support for the heels, means for delivering heels in similar positions upon the support, a conveyor in a plane parallel to the plane of the support, and means above the conveyor for removing the heels from the support, uniformly changing their positions and dropping them similarly positioned upon the conveyor. 95

41. A machine for operating upon heels having, in combination, a support for receiving similarly positioned heels, means for feeding the heels across the support, a belt conveyor, in a plane parallel to the plane of the support, extending at right angles to the direction of feed of the heels, and mechanism for receiving the heels from the feeding means and transferring them to the conveyor. 100

42. A machine for operating upon heels having, in combination, a support upon which the heels rest upon their breast ends, means for feeding the heels across the support, means engaged by the advancing face of the heels for holding the heels under control as they are being fed, a conveyor extending at right angles to the direction of feed of the heels, and means for seizing the heels after they have been fed and transferring them to the conveyor. 110

43. A machine for operating upon heels having, in combination, a support for the heels, means for successively delivering heels with their breast ends resting upon the support, a conveyor, and means for successively removing the heels from the support and depositing them base lift down upon the conveyor. 125

44. A machine for operating upon heels having, in combination, a support for the

heels, means for successively delivering heels with their breast ends resting upon the support, a conveyor, and means for successively removing the heels from the support and depositing them with their rear ends foremost upon the conveyor.

45. A machine for operating upon heels having, in combination, a support for receiving similarly positioned heels, a conveyor, a pusher for engaging a heel upon the support by one of its faces and feeding the heel across the support, a member for yieldingly engaging the opposite face of the heel on the support to maintain the heel under control while it is being fed by the pusher, and a transfer device to which the heels are delivered by the pusher for transferring the heels to the conveyor.

46. A machine for operating upon heels having, in combination, a support for the heels, a conveyor, means for transferring the heels from the support to the conveyor comprising a rotary carrier having a gripper device for holding the heels, means for rotating the carrier to transfer the heels to the conveyor, means for feeding the heels across the support into the field of operations of the gripper device, and means for actuating the gripper device to seize a heel upon the support and to deposit a heel upon the conveyor.

47. A machine for operating upon heels having, in combination, a support to which heels are successively delivered, a conveyor, means including a rotary carrier for transferring the heels from the support to the conveyor, a plurality of gripper devices on the carrier one of which is positioned to receive a heel from the support while another is positioned to deposit a heel upon the conveyor, means for rotating the carrier, and means for actuating the gripper devices to simultaneously seize a heel on the support and deposit a heel upon the conveyor.

48. A machine for operating upon heels having, in combination, a support for the heels, a conveyor, means for transferring the heels from the support to the conveyor comprising a rotary carrier having a pair of gripper jaws for seizing the heels by their opposite lateral edges, and means cooperating with said jaws to support the heels by engagement with one face thereof.

49. A machine for operating upon heels having, in combination, a support to which the heels are delivered breast end down and their top lift faces in advance, a conveyor, and transfer mechanism for removing the heels from the support and depositing them base lift down and breast end rearmost upon the conveyor.

50. A machine for operating upon heels having, in combination, a support upon

which the heels rest upon their breast ends, a conveyor, and means for transferring the heels from the support to the conveyor constructed and arranged to turn the heels through two-thirds of a revolution about an axis inclined at an angle of 45° with respect to the plane of the support and also with respect to a vertical plane normal to the planes of the heel lifts.

51. A machine for operating upon heels having, in combination, a support upon which the heels rest upon their breast ends, a conveyor extending at right angles to a vertical plane normal to the planes of the heel lifts, means for transferring the heels from the support to the conveyor comprising a carrier rotatable about an axis inclined at an angle of 45° with respect to the plane of the support and also with respect to said vertical plane, three pairs of gripper devices mounted upon the carrier at equal distances from each other and constructed and arranged to seize the heels by their opposite lateral edges, means for rotating the carrier, and means for simultaneously actuating two pairs of gripper devices to cause them to respectively seize a heel upon the support and deposit a heel upon the conveyor.

52. A machine for assembling pieces of shoe stock having, in combination, a plurality of open ended tube-like presses in circular series through which the pieces of stock are advanced in column formation, means for feeding the pieces of stock to said presses, means for relatively moving the presses and the feeding means to bring them into a relation for introducing the pieces of stock into said presses, and a plunger for forcing the stock from said feeding means into said presses.

53. A machine of the character described having, in combination, a plurality of tube-like presses through which the pieces of stock are advanced in column formation, means for feeding the pieces of stock to said tube-like presses, means for relatively moving the tube-like presses and the feeding means to bring them into a relation for introducing the pieces of stock into said presses, and means for carrying the pieces of stock from said presses.

54. A heel press having, in combination, a rotatable support, a plurality of tube-like structures carried by the support adapted to receive successive pieces of stock in column formation, and yielding means at the receiving end of each of said structures normally projecting into the interior thereof for engaging the endmost piece of stock as it is received therein to retain it within the structure.
